UNITED STATES PATENT OFFICE.

ADOLPH C. SCHULZ, OF LA SALLE, ILLINOIS.

BOTTLE-STOPPER.

SPECIFICATION forming part of Letters Patent No. 231,451, dated August 24, 1880.

Application filed June 11, 1880. (Model.)

To all whom it may concern:

Be it known that I, ADOLPH C. SCHULZ, of La Salle, in the county of La Salle and State of Illinois, have invented certain new and useful Improvements in Bottle-Stoppers; and I do hereby declare that the following is a full, clear, and exact description of the invention, sufficient to enable others skilled in the art to which it appertains to make and use it, reference being had to the accompanying drawings, and to the letters of reference marked thereon, in which drawings—

Figure 1 is a perspective view of my improvement. Fig. 2 is a similar view thereof with the stopper withdrawn from the bottle. Figs. 3 and 4 are detail views thereof; and Fig. 5 is a sectional view, partly in side view, of my improvement.

This invention relates to improvements in bottle-stoppers; and it consists of a spring-bail adapted to act upon the stopper and with its lower ends passing through a band around the neck of the vessel and entering slots or grooves in the said neck of vessel, said grooves having downward-inclined extensions, while the band to which the bail is connected has a hooked spring adapted to be sprung into one of said grooves, substantially as hereinafter more fully set forth.

In the accompanying drawings, *d* indicates the stopper, with a covered elastic or rubber disk, *c*, secured thereto, with the disk covering the upper edge of the bottle or vessel to render it air-tight around the stopper.

e is a spring-bail, with its upper end formed into a loop, *l*, for convenience to operate it, and which admits of the bail having more or less spring and acting with a degree of pressure when force is applied thereto—as, for instance, to secure it firmly upon the stopper and around the bottle or vessel neck. The lower ends of the bail *e*, which are extended inwardly, enter slots *i*, made in the neck of the bottle, after being passed through a band.

f is the aforesaid band, secured so as to slide 45 upon the neck of the bottle or vessel, with perforations through it to permit of the reception of the inwardly-bent ends of the bail *e*.

The band *f* has a spring, *g*, hooked into one of the slots *i* in the vessel or bottle neck, when 50 the lower ends of the bail are turned into the lower inclined extensions of the said slots.

The slots *i* extend in the direction of the length of the bottle or vessel neck, and are then inclined downwardly at their lower ends, 55 as above intimated, to permit the turning of the bail, so as to cause the lower ends to draw upon its upper end and press downwardly upon the stopper. When in this position the spring *g* is capable of being sprung into the vertical 60 portion of one of the slots *i*, so as to draw laterally upon the neck of the bottle or vessel and in a direction that will prevent the lower ends of the bail *e* rising out of the inclined extensions of the slots *i*, and thus effectually 65 lock the bail down upon and firmly secure the stopper in place in the neck of the bottle or vessel. By springing the spring *g* out of the slot the bail will be released, and the same can be elevated or turned to one side out of 70 the way and permit the stopper to be removed.

Having thus fully described my invention, I claim and desire to secure by Letters Patent—

The combination, with the bottle or vessel neck having the vertical slots *i*, with their lower ends provided with downward-inclined extensions, of the stopper spring-bail *e* *l*, having inwardly-bent ends, and the band *f*, having a hooked spring, *g*, constructed and adapted to operate as and for the purpose specified.

In testimony whereof I affix my signature in presence of two witnesses.

ADOLPH C. SCHULZ.
